UNITED STATES PATENT OFFICE.

STEPHEN C. MENDENHALL, OF RICHMOND, INDIANA.

CASTER.

SPECIFICATION forming part of Letters Patent No. 314,960, dated March 31, 1885.

Application filed October 4, 1884. (No model.)

To all whom it may concern:

Be it known that I, STEPHEN C. MENDENHALL, a citizen of the United States, residing at Richmond, in the county of Wayne and State 5 of Indiana, (present business address Cincinnati, Ohio,) have invented certain new and useful Improvements in Casters for Furniture and other Articles, of which the following is a specification.

This invention relates, primarily, to oscillating two floor-wheel casters; and it consists, more especially, in casting or forming the axle of such a caster with bearings for a vertical anti-friction roller above, and for the horizontal arm of a malleable or wrought iron spindle below. The advantage of this arrangement is that both the oscillating and the anti-friction movement are taken up directly by the axle-piece, much simplifying the construction 15 of such casters. The axle-piece is preferably cast in one piece, of malleable iron, so that the ends of its spindle may be riveted over for retaining the floor-wheels thereon. The spindle employed may have its vertical part either solid or hollow, to engage with a hollow or a solid 20 projection, respectively, from the furniture-plate. The two constructions are equivalent, the main desideratum being to obtain a slight sliding movement between the spindle and the furniture-plate necessary in a construction 25 of oscillating caster in which the whole weight of the furniture is taken up by a vertical anti-friction roller supported on the axle, and the spindle is journaled in a different horizontal plane from said roller. The preferred form of 30 caster, however, for ordinary uses, is one in which the vertical portion of the spindle is solid, to adapt it to occupy a socket in the furniture. Such socket may be formed with a 35 cylindrical neck projecting both above and below the furniture-plate to give both upper and lower bearing to the spindle, and thus increase its rigidity and strength. For plate-casters 40 this construction is modified by omitting the neck above the furniture-plate and riveting the spindle over a washer placed in a socket in the furniture-plate, while for separating casters, intended, principally, for bedsteads and similar articles, a longer furniture-socket is employed to give length of bearing to the spindle, and the neck below the furniture-plate is

omitted, so that when the caster drops apart on lifting the furniture the smooth under surface of the furniture-plate may rest upon the carpet.

The floor-wheel employed in this caster is preferably of glass, which is valuable by reason of its insulating properties. The glass roller is made substantially as described by me in my former application for Letters Patent, 55 filed on the 30th of August, 1884, Serial No. 141,864. I have discovered that in a glass roller made, as described in said application, with a conical ground axial opening, I may employ a correspondingly-shaped bushing of some anti-friction metal—such as brass or Babbitt metal—which, when covered with cement and driven into place, will be held in so rigidly as to prevent withdrawal without breaking the roller. The bushing is preferably driven in solid, and 60 subsequently, so as to insure a true bearing 65 for said spindle.

In order that my invention may be more fully understood, I will proceed to describe it with 70 reference to the accompanying drawings, in which—

Figure I is a perspective view from the rear of the preferred form of my invention as applied to stem-casters. Fig. II is a rear elevation of the caster, with one floor-wheel removed and the other in vertical section. Fig. III is a vertical section of a caster, showing the anti-friction-wheel bearing in side elevation. Fig. IV is a similar view of the invention as applied to a plate-caster. Fig. V is a similar 75 view of a separating caster embodying my invention. Fig. VI is a similar view of a modified form of plate-caster in which the means of attachment of the axle to the furniture-plate 80 is the reverse of that shown in the previous figures. Fig. VII is an axial section of the 85 preferred form of the floor-roller.

The axle-piece 1 of my improved caster in all the forms here shown is cast in one piece, 90 with upwardly-projecting lugs 2, providing bearing for the horizontal pin 3, upon which is journaled the vertical anti-friction wheel or roller 4, situated directly above the axial line of the floor-wheel axle. Below said axial line 95 and transverse thereto is cast or bored a cylindrical bearing for the cylindrical arm 5 of

the spindle 6. The said bearing may be extended both forward and in rear of the axle in the form of necks 7 8, against the former of which abuts an annular shoulder, 9, upon the 5 spindle to keep the proper relative distance between the spindle and the axle. The necks 7 8 provide a long bearing for the spindle-arm, resulting in greater strength and almost frictionless oscillation. The whole axle-piece, as well 10 as its spindles 10, being cast of malleable iron, the ready attachment of the same to the floor-wheels 11 is effected by riveting the ends of the spindles over washers 12, which bear inwardly against shoulders 13 on the spindles to prevent 15 binding on the floor-wheels due to careless riveting. A similar connection is made between the spindle-arm 5 and the axle, the whole spindle being preferably made of malleable or wrought iron, and having a stud, 14, 20 which is riveted over a washer, 15, when the caster is put together. A strong and light caster, having the parts which sustain the strain made wholly of malleable and wrought iron, is thus produced. The effect of placing the 25 oscillating movement immediately underneath the axle is not only to secure greater strength, but to prevent that tipping action of the wheels which is one of the main detrimental features of oscillating two-wheel casters in 30 which the oscillating movement is placed at some distance above the level of the axle. The nearer the oscillating bearing is brought to the floor the more nearly will the point of application of force lie in a line with that of resistance, and the less will be the tendency to tip 35 the axle, and consequently the less danger there will be of stoppage of swiveling of the caster and consequent breakage due to binding between the wheel-housing and furniture 40 plate or spindle.

The spindle employed in the present caster is bent at right angles, and its vertical part is formed solid to engage in a socket, 16, fixed to the furniture, as shown in Figs. I, II, and V, 45 inclusive; or hollow, to receive a pin or stud, 17, projecting downward from the furniture-plate 18, as shown in Fig. VI. It will be seen that the mechanical result of the two constructions is identical—namely, to hold the spindle 50 to an upright position, while allowing its slight vertical movement. Such vertical movement is necessary in the form of caster here shown, in which the whole weight of the furniture rests upon a vertical anti-friction roller. The 55 liberty of such relative movement of the spindle and its socket is here shown somewhat exaggerated. In a caster of ordinary construction the relative movement of these parts will probably be somewhere in the neighborhood 60 of a thirty-second of an inch.

For stem-casters the construction shown in Figs. I, II, and III is preferably employed. In this form the furniture-plate 18 is provided with both upwardly and downwardly projecting necks 16 16^a, so as to afford bearing for them at the top and bottom of the spindle, securing by this means greater strength and free-

dom of swiveling. In this, as well as other forms of caster here shown, the spindle is arranged to bear only on the extreme upper and lower ends of the socket by reason of shoulders 19 20, formed either on the spindle or its socket, or both. In the non-separating casters shown in Figs. III and VI the spindle is retained in its socket by means of a screw or stud, 21, engaging the head or projection 19. 70 75

For plate-casters the upper neck, 16, of the socket is dispensed with, as shown in Fig. IV, and the spindle retained in place by riveting the stud 22, at the top of the spindle, over a washer, 23, placed in a socket in the upper face of the furniture-plate. An equivalent arrangement to this is shown in Fig. VI, the spindle and socket being simply reversed in position and having precisely the same action. 80 85

In Fig. V is shown the application of the invention to a separating caster intended for bedsteads and like purposes. In this the lower neck, 16^a, is dispensed with, and the upper neck, 16, may be made of greater length, as 90 here shown, so as to provide a long bearing for the spindle.

It will be seen that the various forms of casters here shown may be used on various kinds of floor-wheels. I prefer, however, to employ 95 a glass roller by reason of the valuable insulating properties of such a roller. The glass portion of the roller is made in the manner described in my application No. 141,864, already referred to. When the axial opening in the 100 glass is formed and ground to an accurate frusto-conical shape, I drive therein a solid bushing, 24, Fig. VII, made of suitable anti-friction metal—such as brass or Babbitt—cemented on the outside, so as to be held firmly in place. 105 When in place, an axial bearing, 25, is bored in the said bushing for the reception of the spindle of the floor-wheel axle.

Having thus described my invention, the following is what I claim as new therein and desire to secure by Letters Patent: 110

1. In a two-wheel oscillating caster, an axle supporting the floor-wheels, having a transverse cylindrical bearing below the axis of said wheels, and a spindle having an arm occupying 115 said bearing, substantially as and for the purpose set forth.

2. In an oscillating caster, the combination, with two floor-wheels and an anti-friction roller and spindle having a horizontal arm, of an axle 120 having trunnions for the floor-wheels and bearing for the vertical anti-friction wheel or wheels also formed integrally with the axle, and a transverse cylindrical bearing for the spindle-arm below the center of the floor-wheels, substantially as and for the purpose set forth. 125

3. The combination, with an axle-piece made of malleable or wrought iron, and having trunnions and bearings for the floor-wheels and anti-friction roller, respectively, formed integrally therewith, of a malleable or wrought iron spindle occupying a socket in the axle, and connected to said axle by riveting, substantially as described. 130

4. The combination of an axle, two floor-wheels, and a vertical anti-friction roller mounted thereon, a spindle occupying a bearing in said axle below the center of the floor-wheels, a furniture-plate resting on said anti-friction roller, and a downwardly-projecting neck surrounding and bracing the lower end of the spindle, substantially as set forth.
5. In combination with an axle having a vertical anti-friction roller and a horizontal arm journaled thereon in different horizontal planes, a rigid vertical projection from said horizontal arm, and a furniture-plate having

a rigid downward projection engaging with the projection from the arm in the axle or 15 housing in such a manner as to allow vertical movement between the two.

6. In a caster, the combination, with the spindle having a horizontal arm, of an axle having a transverse bearing for said arm, and a 20 neck or extension surrounding said arm, substantially as and for the purpose set forth.

STEPHEN C. MENDENHALL.
